The ornamental design for a clothes dryer, as shown and described.

DESCRIPTION

FIG. 1 is the front/right-side/top perspective view of a clothes dryer showing our new design;

FIG. 2 is the front elevational view thereof;

FIG. 3 is the rear elevational view thereof;

FIG. 4 is the left-side elevational view thereof;

FIG. 5 is the right-side elevational view thereof;

FIG. 6 is a top plan view thereof; and,

FIG. 7 is the bottom plan view thereof.

The shade lines in the Figures show the transparency and the flatness, and not surface ornamentation.

The broken lines shown in the drawings represent unclaimed portions of clothes dryer.
